UNITED STATES PATENT OFFICE.

ANGELO M. TOZZI, OF BAYONNE, NEW JERSEY.

STYLUS FOR SOUND-REPRODUCING MACHINES.

1,284,820.

Specification of Letters Patent. Patented Nov. 12, 1916.

Application filed October 19, 1916. Serial No. 126,467.

To all whom it may concern:

Be it known that I, ANGELO M. TOZZI, a subject of the King of Italy, and resident of Bayonne, in the county of Hudson and State of New Jersey, have invented certain new and useful Improvements in Styli for Sound-Reproducing Machines, of which the following is a specification.

This invention relates to a stylus for sound reproducing machines; my object being to provide a hard durable stylus whereby tone quality is preserved and whereby wide variability of tone volume may be attained.

Accordingly my invention, generally stated, comprises a stylus composed of a stem or tang merging with a tapering concavo-convex portion terminating in a track point.

The invention also comprises features of construction which will be hereinafter described and claimed.

In the annexed drawings—

Figure 1 is a side elevation of a stylus embodying the preferred form of my invention, the device being illustrated as associated with a sound box and in playing position upon a record.

Fig. 2 is a transverse section through the stem or tang of the stylus, as on the line 2—2 of Fig. 1.

Fig. 3 is a similar section through the concavo-convex extension, as on the line 3—3 of Fig. 1.

Figs. 4, 5 and 6 are elevations of the stylus, on a larger scale, showing it in different playing positions in order to vary the tone volume.

Referring to the drawings, A designates a sound box of any usual or approved construction; B my improved stylus as applied thereto, and C a part of a record with the track of which the stylus is engaged.

The stylus, in the typical form illustrated, comprises a tubular stem or tang 10 having a sectional extension 11 longitudinally thereof of terminating in a point 12, the whole being composed of a single piece of sheet metal appropriately shaped, hardened, ground and polished. The extension is concavo-convex in cross-section throughout the greater part of its length, its longitudinal tapering edges presenting compound curves which diverge gradually from the point toward and merge with the body of the stem as illustrated. The bulged portions 13 of the edges of the extension augment the transverse strength of the latter in a plane between the point and the

root of the extension, and hence the resiliency of the stylus is largely localized below such portions when the point is engaged with and acted upon by the track of a traveling record.

A stylus constructed with a concavo-convex extension as above set forth may be hardened to a high degree and thus be repeatedly used without appreciable abrasion of its point by the frictional action thereon of the record; whereas the ordinary pointed cylindrical needle, which is necessarily made relatively soft to avoid liability of breaking the point, (and is thus rapidly abraded by frictional contact with the record) can be used for a brief period only.

Apart from this important feature of durability, my improved stylus insures tone quality and permits numerous changes in tone volume in the operation of a sound reproducing machine.

Tone quality results from the peculiar contour of the sectional extension of the tubular stem whereby the axis of vibration of the point is largely localized in the lower portion of the extension and the sound waves are uniformly distributed and transmitted to the tubular stem. Thus liability of "blasting" in the reproduction of sound is obviated; or, in other words, the stylus, acting as a shock absorber, eliminates shrill or strident tones.

Variations in tone volume can be readily effected by changing the position of the stylus in relation to the path of the record; that is to say, if the stylus be positioned as in Fig. 1, with the concave side of the extension downward, the point will bear resiliently against the record and thus effect a mild reproduction similarly to a "soft" needle; if the stylus be positioned with the concave portion upward, as in Fig. 4 the point will bear more rigidly against the record and effect a sharp reproduction similarly to a "hard" needle, and if the stylus be positioned with its concave portion presented outwardly as in Fig. 5, or inwardly as in Fig. 6 the bearing action of the needle in each case will be modified to produce respectively intermediate tone volumes. And similarly, by adjusting the stylus to vary the position of the point about the longitudinal axis of the stylus, a multiplicity of changes in tone volume can be efficiently produced, as occasion may require.

It is to be understood that the details of

construction may be varied within the principle of my invention and the scope of the appended claims.

I claim—

- 5 1. A stylus of the character described comprising a stem having a tapering concavo-convex extension terminating in a track point, the edges of such portion presenting compound curves the bulges of which augment the strength of the extension in a plane between the point and the root of the extension, whereby the axis of vibration of the point is largely localized below said bulges.
- 10 10. A stylus of the character described

comprising a tubular stem having a tapering concavo-convex extension terminating in a track point, the edges of such portion presenting compound curves the bulges of which augment the strength of the extension in a plane between the point and the root of the extension, whereby the axis of vibration of the point is largely localized below said bulges. 15 20

Signed at New York, in the county and State of New York, this 18th day of October, 25 A. D. 1916.

ANGELO M. TOZZI.
